UNITED STATES PATENT OFFICE.

DAVID R. STEELE, OF WATERLOO, NEW YORK.

CLUTCH-CONTROLLER.

SPECIFICATION forming part of Letters Patent No. 425,465, dated April 15, 1890.

Application filed August 30, 1889. Serial No. 322,445. (No model.)

To all whom it may concern:

Be it known that I, DAVID R. STEELE, a citizen of the United States, and a resident of Waterloo, in the county of Seneca and State 5 of New York, have invented certain new and useful Improvements in Clutch-Controllers, of which the following is a specification.

My invention relates to the means employed for controlling or setting and releasing 10 clutches, so as to render them alternately operative and inoperative.

Hitherto clutch devices have been variously constructed. In the accompanying drawings I have shown a frictional clutch, such as has 15 heretofore been employed for rotating the drum of hoisting machines or engines, and I have also there shown such a machine sufficiently to indicate one way in which my improvements may be reduced to practice, all 20 of which I will hereinafter more fully describe and explain.

In the accompanying drawings, Figure 1 is a side elevation of so much of a hoisting machine or engine embodying my improvements 25 as will illustrate one mode of applying my invention to use. Fig. 2 is a vertical central longitudinal section of the same. Fig. 3 is a like representation, enlarged, and more clearly showing those parts which embrace my invention; and Fig. 4 is a section in the plane of the line $x x$ of Fig. 3, viewed in the direction indicated by the arrow there shown.

Like letters of reference indicate like parts. A represents the frame of the machine.

B is a rotary shaft mounted in fixed bearings $a a$. One end or portion of this shaft is 35 hollow or bored out longitudinally, as indicated at b , Figs. 3 and 4, and $c c$ are slots entering the inner part of the tubular portion 40 of the shaft, which may be termed the "drum-shaft," as will hereinafter more fully appear.

C is a gear-wheel keyed to and turning with the shaft B on the inner side of the wheel C, and rigidly attached thereto is a male cone C' , 45 constituting one member of the clutch device.

D is a drum, on one end of which is a female cone D' , adapted to engage with the cone C' , as is usual in frictional clutches of this class.

E is a flange or guard on the other end of 50 the drum.

F is a cylindrical bar entering and adapted to turn freely in the chamber b , and d is an annular groove in the said bar near its inner end.

⁵⁵
 e is a screw-thread on the said bar near its outer end.

G is a nut upon the screw e . This nut is rendered fixed or immovable by being attached to the frame or other fixed part in any 60 suitable way—for example, by means of small rods $f f$ and nuts $g g$, as is clearly shown in the drawings.

H is a handle or lever keyed or fastened to the outer end of the bar F.

⁶⁵
The part D' may be termed the "sliding member" of the clutch.

I I are loose blocks or keys made to enter the groove d and to overlap the enlarged inner end of the bar F.

⁷⁰
 J is a cap or retainer screwed or otherwise securely fastened to a flanged piece or hub K, rigidly or firmly attached to the drum D and rotating with it, it being understood that the cap J is loose upon the shaft B and turns with 75 the said hub. It will be observed that the blocks I I project through the slots $c c$, and enter a space between the end of the hub and the head of the cap; but these blocks are small enough to permit the free rotation referred to, and the said slots are long enough to permit a forward and backward movement of the blocks. The function of the cap is simply to retain the blocks in their proper places, and I would regard any other retainer 85 performing that function as the equivalent of that shown. I may also here explain that the blocks I I perform the function of sliding the drum into or out of frictional contact with the cone C' , as the rod F is moved back or 90 forth by being rotated in the nut G, as will hereinafter more fully appear; and I do not, therefore, here intend to confine myself to the particular form shown of the parts co-operating with that result. The cap J , and the piece to which it is attached, may be termed 95 a "recessed" or "chambered" extension or hub of the drum D. It will now be perceived that by rocking the handle H in one direction slightly the bar or rod F will be to 100 that extent rotated, and that as the screw e upon it is thus turned in the nut G, which is

stationary or fixed, the bar will, for example, be advanced in the direction of the cone C', and that the blocks I I by entering the cap J in the manner described will push the drum in the same direction until it is clutched by the said cone sufficiently to be rotated and to lift its load; also, that when the handle is rotated in the opposite direction the drum will be pulled from the said cone and be free to rotate in the reverse direction. In other words, there is a positive push or pull connection or engagement between the sliding member D' of the clutch and the handle H. A slight movement of the handle and a slight force applied to it will be sufficient to render the clutch either operative or inoperative, as may be desired or necessary. It will also be perceived that a double drum may be controlled in like manner, and that the wheel C 20 may be driven in any suitable or well known way.

25 I desire to state, further, that two blocks or keys I I are not absolutely essential, as one would be operative for the purposes set forth; but I regard it as preferable to employ two,

as the push and pull would then be more easy, being derived from oppositely-arranged blocks.

Having thus described my invention, what I claim as new, and desire to secure by Letters Patent, is—

The combination, in a hoisting-machine, of a drum-shaft B, having a slotted hollow portion b, the sliding drum D, loosely mounted on the said shaft and having on one end 35 thereof the cap or retainer J, the screw-rod F, the fixed nut G, engaging the said rod, and one or more blocks or keys I I, engaging the said rod loosely and freely entering the said cap behind its flange or outer rim, the said drum and its driver being adapted for frictional engagement with each other, substantially as and for the purposes specified.

Signed at Waterloo, in the county of Seneca and State of New York, this 26th day of Au- 45 gust, A. D. 1889.

DAVID R. STEELE.
